(57) CLAIM

I claim the ornamental design for a computer game accessory, as shown and described.

DESCRIPTION

FIG. 1 is a top view showing my new design;

FIG. 2 is a front view thereof;

FIG. 3 is bottom view thereof;

FIG. 4 is a perspective view thereof; and,

FIG. 5 is a side view thereof.

The portions of the computer game accessory shown in broken line in the Figures form no part of the claimed design.

1 Claim, 5 Drawing Sheets

FIG. 1

FIG. 2

FIG. 3

FIG. 4

FIG. 5
